WINFIELD S. RYNEARSON, OF EDMONDS, WASHINGTON.

COLLAPSIBLE TENT SUPPORT.

Application filed February 9, 1926. Serial No. 87,158.

This invention pertains to supports for tents, and refers more particularly to an improvement in the ordinary form of three-pole tent supports which includes a pair of uprights and a ridge pole.

The outstanding object of the present invention is to provide a tent support which is collapsible to occupy a minimum amount of space when not in use so that the same may be readily transported or stored and this without weakening the support or entailing an unnecessary length of time in setting the same up for use.

The invention further comprehends a tent supporting means including a ridge pole and upright supporting poles, each constructed of joined sections capable of being readily associated or disassociated and in which means is provided for guiding the user in properly associating the sections when disjointed, the invention furthermore contemplating particularly in connection with the ridge pole, means for retaining the ridge pole sections in jointed associated relation to preclude separation thereof when in use, which means further functions to bind the sections in compact bundles when the parts are in knockdown condition.

As it is ordinarily desirable to construct tent poles of wood and it has been found to be more practical to employ metal ferrules for telescopically associating the poles when made in sections, it is obvious that in the ridge pole construction the metal ferrules would contact with the canvas, and to this end the invention contemplates a ridge pole construction which while using metal ferrules, employs them in such a manner as to prevent their contact with the canvas.

Other objects of the invention reside in the simplicity of the construction and mode of use of the invention, the economy with which the same may be manufactured and the general efficiency obtained.

With the above recited and other objects in view, reference is had to the following specification and accompanying drawings in which there is exhibited one example or embodiment of the invention which is in no way intended as a limitation upon the scope of the appended claims as it is to be clearly understood that variations and modifications which properly fall within the scope of said claims may be resorted to when found expedient.

In the drawings—

Figure 1 is a side view of a tent support constructed in accordance with the invention and illustrating the same in set-up condition;

Fig. 2 is a plan view thereof;

Fig. 3 is a perspective view of the ridge pole with certain of the sections disjointed or disassociated;

Fig. 4 is a fragmentary longitudinal sectional view through and illustrating the joint between the ridge pole sections;

Fig. 5 is a perspective view of one of the upright poles disconnected from the ridge pole and with the same partly disjointed or disassembled;

Fig. 6 is a longitudinal sectional view through and illustrating one of the ridge pole joints.

Referring to the drawings by characters of reference, A designates generally a ridge pole, and B the upright supporting poles therefor, which poles B are associated in the usual manner by the engagement of the upwardly projecting pins C on the upright poles through the vertical receiving openings D in the opposite ends of the ridge pole. The invention pertains particularly to the jointed construction of the ridge and upright poles A and B whereby the same may be disjointed and collapsed for the obvious purpose specified.

The ridge pole A consists of a plurality of sections preferably constructed of wood, which as illustrated by way of example, comprise a pair of identically constructed outer sections 10, identically constructed intermediate sections 11, and a single central section 12. The outer sections 10 each consist preferably of a rectangular bar in the outer end of which the vertical receiving opening D is provided for the upright pin C, the inner end being bifurcated to provide upper and lower furcations 13 and 14, the latter being of greater length than the former and of reduced cross-sectional size. The intermediate sections 11 each consist of a bar or length of wood of the same cross-sectional configuration and size as the sections 10 and formed, respectively, at the outer and inner ends with bifurcated terminals providing upper and lower furcations 15 and 16 at the outer ends and 17 and 18 at the inner ends, the upper furcation 15 at the outer end projecting beyond the lower furcation 16, which latter

furcation is of lesser cross-sectional size than the furcation 15 and corresponds approximately to the cross-sectional size of the furcations 14 of the sections 10. A metal ferrule 19 surrounds the furcation 16, projects beyond the outer end thereof and beyond the outer end of the upper furcation 15, the portion of said ferrule 19 projecting beyond the outer end of the furcation 16 a distance approximately equal to the length of the lower furcation 14, while the inner end of the ferrule is secured to the furcation 16 in any suitable manner. The opposite inner bifurcated end of each intermediate section 11 including the furcations 17 and 18, are of identical construction to the bifurcated inner end of the outer sections 10, that is, the lower furcation 18 is of greater length than the upper furcation 17 and of reduced cross-sectional size. The center section 12 is provided at its opposite ends with identically constructed bifurcated terminals including upper and lower furcations 20 and 21, the former being of greater length than the latter and the latter being of reduced cross-sectional size with respect to the former, said lower furcations 21 having fitted thereover metal ferrules 22 extending beyond the ends of the upper furcations and presenting terminals at the opposite ends of the center section 12 identical with the construction of the outer terminals of the intermediate sections. This construction of the ridge pole admits of the joining or association or disjoining or disassociation of the sections which are constructed of wood, by metal ferrules, but disposes said ferrules in such a position that the upper edge of the ridge pole over which the canvas is stretched is composed entirely of wood so as to prevent contact of the canvas with the metal ferrules.

In order to provide means for guiding the user in properly associating or assembling the sections of the ridge pole and to prevent their entire separation while allowing for the disjoining thereof, a pair of flexible elements such as cords 23 are employed, each of which is connected at its outer end at 24, adjacent to the inner end and to the under side of the outer sections 10. The cords are trained through guide elements such as staples 25 on the under side of the intermediate section and on the under side of the center section, the inner end of the cords being provided with a loop beyond the guide element or staple which prevents the pulling of the cord completely through the guide element on the center section and limits the relative separation of the sections. Incidentally one of the staples 25 on the intermediate section and the staples 25 on the center section pass through the ferrules 19 and 22 respectively, and are anchored in the furcations which they surround to con-

stitute means for preventing displacement of the ferrules from said furcations.

In order to provide retaining means for holding the adjacent sections of the ridge pole against disjoining when they are telescopically fitted together as illustrated in Figures 1 and 2, strap sections 27 are trained through the loops 26 at the inner ends of the cords 23, and through guides 28 on the side of the intermediate sections, said straps having a buckle 29 at one terminal and perforations 30 in the opposite terminal adapted to be interengaged to draw the cords 23 taut after the sections are jointed. Preferably the guides 28 are disposed on opposite sides of the respective intermediate sections by which they are carried so that the straps will be consequently disposed on opposite sides of the ridge pole and in a non-interfering relation when in use.

When setting up the ridge pole when the sections are disjointed, the cords 23 constitute a guide means which insures a proper association of the sections with each other. The sections 18 at the inner ends of the intermediate sections 11 are telescopically engaged in the ferrules 22 until the ends of the furcations 17 and 20 are brought into abutting relation. The lower furcations 14 of the outer sections 10 are inserted in the ferrules 19 until the inner ends of the upper furcations 18 abut with the outer ends of the upper furcations 15 of the intermediate sections 11. By then engaging the straps through the guides 28 and buckling the same tight, it is obvious that the cords 23 are drawn taut to maintain the sections of the ridge pole against disjoining.

The upright poles B consist of upper, lower and central sections 31, 32 and 33, the uppermost section having at its upper end the upstanding or upwardly projecting pin C and formed at its lower end with a terminal 34 of reduced cross-sectional diameter adapted to be received or telescopically engaged in a metal ferrule 35 which is secured to and projects beyond the cross-sectional reduced upper terminal 36 at the upper end of the central section 33 a distance approximately equal to the length of the reduced terminal 34 of said upper section. The central section 33 is provided with a lower terminal 37 of reduced cross-sectional size, which is designed to fit within the ferrule 38 formed on the lower section 32 to correspond to the ferrule 35 on the central section, the lower end of the lower section 32 being provided with a pointed terminal 39 adapted to be driven and anchored in the ground. In order to provide means for guiding the user in properly associating the sections of the upright poles and in order to prevent complete separation of the sections while permitting of sufficient relative movement to allow for disjoining, the upper section 31

of each pole B has secured thereto adjacent its lower end, at 40, one extremity of a flexible element 41, such as a cord, the opposite end of which is trained through a guide 42 on the intermediate section and is knotted or otherwise formed with an enlargement 43 which prevents complete withdrawal of the cord therefrom while allowing for sufficient movement to disjoint. The sections 32 and 33 are similarly jointed and it is obvious that after the sections have been associated, the free ends of the cords may be tied, if desired, to hold and maintain the sections against disjointing.

When the sections of the ridge pole and the upright poles are disjointed and arranged in side-by-side or parallel relation, it is obvious that the straps 27 may be employed as binders to encompass and hold all of the sections in a compact bundle for transportation or storage. While the ridge pole and uprights have been described as consisting of a certain number of sections, it is obvious that it is within the scope of the invention to increase or decrease the length of the poles by adding to or subtracting certain sections therefrom.

What is claimed is:

1. A tent supporting means including collapsible ridge and upright poles, said poles consisting of telescopically associated sections, means for guiding the user in properly associating the sections, said means comprising flexible connections between the sections permitting of engagement and disengagement of the sections, and retaining means for holding the adjacent sections of the ridge pole against disengagement when telescopically fitted together, said retaining means consisting of elements connected with the guiding means and keepers with which the elements coact to effect the retention of the guiding means in taut condition.

2. A tent supporting means including a ridge pole and upright poles, the ridge pole including a plurality of sections having the adjacent ends bifurcated vertically, the lower furcations being telescopically jointed and the upper furcations adapted for abutting relation.

3. A tent supporting means including a ridge pole and upright poles, the ridge pole including a plurality of sections having the adjacent ends bifurcated vertically, the lower furcations being telescopically jointed and the upper furcations adapted for abutting relation, and means for guiding the user in properly associating the sections, consisting of flexible elements secured to the outer sections, guide eyes on the remaining sections through which the flexible elements are trained and enlargements on the inner ends of the flexible elements for permitting of disjointing of the sections while preventing their complete separation.

4. A tent supporting means including a ridge pole and upright poles, the ridge pole including a plurality of sections having the adjacent ends bifurcated vertically, the lower furcations being telescopically jointed and the upper furcations adapted for abutting relation, means for guiding the user in properly associating the sections, consisting of flexible elements secured to the outer sections, guide eyes on the remaining sections through which the flexible elements are trained and enlargements on the inner ends of the flexible elements for permitting of disjointing of the sections while preventing their complete separation, and retaining means for holding the sections in jointed relation connected with the inner ends of the flexible elements and engageable in keepers on the sides of certain of said sections.

WINFIELD S. RYNEARSON.
